The Timken Roller Bearing Company, Canton,
Ohio, a corporation of Ohio

Application June 12, 1941, Serial No. 397,714

4 Claims. (Cl. 264—14)

This invention relates to hydraulic speed governors for internal combustion engines, particularly compression ignition engines of the type having fuel injection systems including a fuel injection pump wherein part of the fuel entrapped in the pump during the working stroke thereof is diverted through a by-pass to thereby vary the output of the pump and thus regulate the speed of the engine. The principal object of the invention is a governor that will utilize the by-pass pressure of such fuel injection pumps for automatically controlling the speed of the engine. Other objects are simplicity and cheapness of construction and compactness of design. The invention consists in the hydraulic governor and in the construction, combinations and arrangements of parts hereinafter described and claimed.

In the accompanying drawings, which form part of this specification and wherein like symbols refer to like parts wherever they occur,

Fig. 1 is a top plan view of a hydraulic speed governor embodying my invention;

Fig. 2 is an end elevational view of said governor;

Fig. 3 is a side elevational view of said governor;

Fig. 4 is an enlarged central vertical longitudinal section through said governor on the line 4—4 in Fig. 2, showing the governor connected to the fuel feed control pinion and by-pass passageway of a fuel injection pump;

Fig. 5 is a horizontal section on the line 5—5 in Fig. 4;

Fig. 6 is a horizontal section on the line 6—6 in Fig. 4;

Fig. 7 is a horizontal section on the line 7—7 in Fig. 4;

Fig. 8 is a perspective view of the link which connects the governor piston to the sector pinion 40 of the pump;

Fig. 9 is a top plan view of the throttle valve;

Fig. 10 is an edge view of said valve;

Fig. 11 is a top plan view of the inner member of the breather cap;

Fig. 12 is a side elevational view of the lower end portion of the throttle shaft;

Fig. 13 is a bottom plan view of said throttle shaft;

Fig. 14 is a side elevational view, partly in longitudinal section, of one of the retaining plates for the pivot pin that connects the piston actuated link to the sector pinion; and

Fig. 15 is a diagram illustrating the different hydraulic pressures brought about by changing

the size of the discharge orifice of the by-pass passageway in the governor.

The hydraulic governor illustrated in the accompanying drawings is adapted to be embodied in the fuel supply system of a compression ignition engine for automatically regulating the speed of the engine by controlling the volume of fuel delivered thereto by the injection pump, of which only the oscillatory fuel feed control sector pinion 81, the manually operable horizontal control shaft 82 therefor and the fuel by-pass conduit 38 are shown. Said fuel injection pump is of the type wherein the quantity of fuel delivered thereby to the engine is controlled by permitting part of the fuel trapped in the pump during the working stroke thereof to escape through the by-pass conduit 38, and the quantity of fuel by-passed, and consequently the amount of the fuel delivered to the engine, is regulated by means of the sector pinion 81. For a further description of a pump with such by-pass regulation, reference is made to my co-pending application, Serial No. 364,232, filed November 4, 1940, for patent for Fuel injection pump, the present governor being designed particularly for use with the pump of said application.

The present governor comprises a housing 1 having an outstanding flange 2 at one end thereof adapted to be rigidly secured to one end of the fuel injection pump of my co-pending application, Serial No. 364,232. The housing 1 has a chamber 3 in the lower portion thereof that opens through the pump opposing end of said housing and is adapted to communicate with the oil reservoir of said pump and receive the adjacent end of the cam shaft thereof. The housing 1 has a horizontal bore 4 therein above the chamber 3, which bore is located in the plane of and at right angles to the axis of the control shaft 82 and opens through the pump opposing end of said housing and is adapted to slidably support a piston 5 which cooperates with said bore to form a pressure space or chamber 4a inwardly of said piston. The housing 1 has a passageway 6 therein above the bore 4, which passageway extends inwardly from the pump opposing end of said housing where it is suitably connected to and forms a continuation of the by-pass conduit 38 of the pump.

The passageway 6 leads inwardly from the pump opposing end of the housing at a downward inclination and opens into a vertical passageway 7, whose lower end opens into the pressure space or chamber 4a. The upper end of the vertical passageway 7 opens through an orifice 7a

into the bottom of a vertical bore 8, which leads downwardly through an upstanding boss 9 on the upper end of the housing 1, said orifice being offset from the vertical axis of said bore. The housing 1 also has a horizontal passageway 10 therein that leads from the lower portion of the vertical bore 8 and opens through the end of the housing remote from the pump opposing end thereof. The horizontal passageway 10 communicates at its outer end with a conduit or pipe 11 for returning the by-pass fuel to the supply tank (not shown) for the fuel injection pump.

Seated on the bottom of the vertical bore 8, which communicates with the upper end of the vertical passageway 1, is a throttle valve comprising a circular disk 12 having a diametral groove 13 in the upper surface thereof and a pair of relatively deep V-shaped notches 14 in the peripheral edge thereof disposed one on each side of said groove. The peripheral notches 14 in the rotary throttle valve 12 are adapted, when in communication with the upper end of the vertical passageway 1, to establish communication between said passageway and the portion of the vertical bore 8 in which said valve is located. The V-shape of the notches 14 in the edge of the throttle valve 12 permits the size of the opening between the upper end of the vertical passageway 1 and the bottom of the vertical bore 8 to be varied when the valve is rotated in said bore.

The throttle valve 12 is rotated by means of a shaft 15 mounted in the vertical bore 8 concentric therewith. The lower end of the throttle valve shaft 15 has an enlarged cylindrical portion 16 with a downwardly opening central cylindrical recess 17 therein; and this enlarged cylindrical portion has a rotary fit in the vertical bore 8 opposite the horizontal passageway 10 leading therefrom and has diametrically opposed lugs 18 at its lower end that seat in the diametral groove 13 in the upper face of the throttle valve 12, whereby said valve is forced to rotate with said throttle shaft. Communication is established between the horizontal outlet passageway 10 and the central recess 17 in the enlarged lower end portion 16 of the throttle shaft 15 through radial passageways 19 therein that lead from said recess and open into an external annular groove 20 formed in said enlarged lower end portion of said shaft opposite the inner end of said outlet passageway.

The throttle valve 12 is pressed against its seat in the bottom of the bore 8 by means of a coil compression spring 21 located in the central downwardly opening recess 17 in the enlarged lower end 16 of the throttle shaft 15. The upper or stem portion of the throttle shaft rotates in a bushing 22 located in the housing by means of a set screw 23 which is threaded radially into the bushing 22 but projects out through a radial hole in the boss 9. The upper end of the bore is counterbored, as at 24, to receive the bushing 22, whose lower end portion is counterbored to receive oil and dust seals in the form of felt bushings 25 that are sleeved on the stem portion of the throttle shaft 15. A washer 26 is sleeved on the stem of the throttle shaft 15 in endwise abutting relation to the lowermost seal 25 and the enlarged lower end portion 16 of said shaft. The outer marginal portion of the washer 26 seats on the annular shoulder formed by the counterbored upper end of the bore 8, and a rubber ring or gasket 27 seats in an external peripheral groove provided therefor in the lower end of the bush-

ing 22 with its lower end in abutting relation to the upper surface of the outer marginal portion of said washer.

The upstanding cylindrical throttle shaft receiving boss 9 at the top of the housing 1 has its upper end portion reduced, as at 28, to receive a split ring 29 which is firmly clamped around said boss by means of a clamp screw 30. The reduced ring receiving upper end portion 28 of the boss 9 is also slit vertically, as at 31, so that tightening of the split ring 29 causes the split portion of the boss to clamp the bushing 22 and prevent or take up any looseness of said bushing in the counterbored upper end portion 24 of the bore 8 in said boss.

The throttle shaft 15 extends above the upper end of the bushing 22 and has a throttle lever 32 fixed thereto. The cooperating portions of the shaft 15 and lever 32 are provided with interfitting longitudinal ribs and grooves 33, whereby said lever may be angularly adjusted on said shaft. The hub portion of the lever 32 is split and provided with a clamping screw 34 for locking said lever to the shaft 15 in the desired position of angular adjustment. The hub portion of the throttle lever 32 has a lug 35 projecting laterally therefrom through which is threaded a stop screw 36; and the split clamping ring 29 has an upstanding lug 37 thereon that is disposed in the path of travel of said stop screw and serves to limit the swinging movement of said lever in one direction. When the lever 32 is swung in the opposite direction, the arm thereof abuts against the upstanding lug 37, which thus limits the swinging movement of said lever in such direction.

The governor housing 1 has a vertical passageway 38 leading downwardly through the upper end thereof into the interior thereof through which oil may be poured for lubricating the injection pump. This passageway also serves as a vent for the governor and also for the injection pump controlled thereby. The passageway 38 has a tube 40 pressed in the upper end thereof that extends upwardly therebeyond and is adapted to receive a breather cap 41. This cap comprises a downwardly opening outer shell member 42 and a smaller downwardly opening inner shell member 43 that is riveted to the top of said outer shell member. The annular space between the inner and outer shell members of the cap is filled with copper wool filtering material 44, and the inner shell member has an outstanding base flange 45 that extends across said annular space and retains said filtering material therein. As shown in the drawings, the inner shell member 43 has its side walls slit vertically, as at 46, and pressed outwardly to form a hollow annular rib 47 adapted to snap over an external peripheral bead on the breather tube 40. By this arrangement, the cap 41 is adapted for giving attachment to and detachment from the breather tube 40.

The piston 5, which works in the horizontal bore or cylinder 4 in the governor housing 1, is an outwardly opening cup-shaped piston having an axial opening 48 in the end wall thereof adapted to receive a connecting stud 49 having a threaded shank portion 50 that extends inwardly beyond said end wall and a head portion 51 that is disposed inside of said piston. A gasket is sleeved on the stud 49 between the head portion 51 thereof and the opposing face of the end wall of the piston 5, a split lock washer 52 is mounted on said stud on the opposite face of said end wall, and a ring nut 53 is threaded on the thread-

ed shank 58 of said stud and serves to rigidly secure the latter to said piston. The piston 5 has a rubber packing ring 54 fixed to the end wall thereof. This rubber packing ring snugly fits the cylindrical wall of the pressure space or chamber 4a and is tightly clamped by the nut 53 to the end wall of the piston 5 around the stud receiving opening 48 therein, thereby preventing leakage from said chamber around said piston and through said opening.

Inward sliding movement of the piston 5 is limited by an adjustable stop in the form of a screw 55 that is threaded into a threaded bore provided therefor in the governor housing 1 with its inner end extending through the inner end wall of the pressure space or chamber in position to be engaged by the inner end face of the clamping nut 53. This stop screw is locked in the desired position of adjustment by means of a castellated nut 56, which bears against and is held against rotation on said screw by a cotter pin 57. Leakage of fuel around the stop screw 55 is prevented by a rubber sealing ring or washer 58 that is held under compression by the nut 53 in a recess formed by a counterbore at the outer end of the stop screw receiving bore.

The pressure of the by-passed fuel in the chamber 4a tends to force the piston 5 outwardly in the bore or cylinder 4a against the the pressure of a coil compression spring 59, one end of which seats against the end wall of the piston and the other end of which seats against a seat 60 provided therefor in the bore outwardly of the piston. The spring seat member 60 is held in the outer end of the bore 4 by means of a split retaining ring 61 that is snapped in an annular groove provided therefor in said bore. As shown in the drawings, the spring seat member 60 is in the form of a cylindrical shell located directly below the breather and oil passageway 39. The inner end portion of the tubular spring seat 60 is reduced to provide a seat for the spring 59 and to establish communication between the breather passageway 39 and the outer end of the bore 4; and the larger outer end of said spring seat is cut away so as not to block said breather passageway and to provide a series of circumferentially spaced fingers 62 that seat in said outer end of said bore.

Outward movement of the piston 5 in the bore is further resisted by a coil tension spring 63, one end of which is threaded on the threaded shank 50 of the stud 49 and the other end of which is threaded on an exteriorly threaded sleeve or ring 64 that is sleeved on an adjusting screw 65 that is threaded through the governor housing 1 in axial alignment with said stud. The adjusting screw 65 has a headed inner end 66 that is disposed in the chamber 4a or a smaller axial extension 4b thereof; and the idle or surge spring connector sleeve or ring 64 is sleeved on said screw and is held in abutting relation to said head by the tension of said spring. The surge spring adjusting screw 65 has a castellated lock nut 67 threaded thereon in abutting relation to the end face of the housing 1; and relative rotary movement of said nut and screw is prevented by means of a cotter key. Leakage around the adjusting screw 65 is prevented by means of a rubber sealing ring 68 that is held under compression by the nut 67 in a recess formed by a counterbore in the outer end of the threaded bore for said screw.

The head 51 of the stud 49 is bifurcated to receive one end of a link 70 which is pivotally secured to said bifurcated portion by means of a

horizontal pivot pin 71. The other end of the link 70 fits in a bifurcated radial lug 95 on the hub of the sector pinion 81 and is pivotally secured to said lug by means of a pivot pin 96 that extends through registering holes 96a provided therefor in said link and in the bifurcated portion of said lug above the level of the rotary axis of the sector pinion 81. The pivot pin 96 has an axial bore extending therethrough from end to end thereof. This tubular pivot pin has a head at one end, which seats against one side of the lug 95, while the other end of said pin terminates beyond the other side of said lug. The pivot pin 96 is held in position by means of two spring steel retaining plates 97, that are secured at one end to the respective side faces of the lug 95 by screws 98 extending through openings provided therefor in the respective links and washers 98a interposed between said links and said lug and are threaded into opposite ends of a hole 95a that extends through said lug from side to side thereof. The retaining plates 97 have conical bosses 99 in their other ends that seat in the adjacent ends of the axial bore in the pivot pin 96. The pivot pin 96 may be inserted in and removed from the housing 1 through openings 1a that open into the bore 4 from opposite sides of said housing and are closed by threaded plugs 1b. As shown in the drawings, the bifurcated portion of the retaining plate supporting lug 95 on the hub of the sector pinion 81 has a second pair of aligned holes 96b that are similar to the holes 96a and are located below the level of the sector pinion axis. The upper pair of holes 96a are used for the pivot pin 96 where proper governor control of the injection pump requires rotation of the sector pinion 81 in one direction, while the lower pair of holes 96b are used when said pinion must be rotated in the opposite direction. As shown in the drawings, the link 70 has a flat face 70a at the inner end thereof adapted to bear against the head 51 of the stud 49 and thus maintain the pivotal connection 96 between said link and the sector pinion 81 above the level of the axis of the latter. When the pivot pin 96 is engaged with the lower set of holes 96b, the link 70 is inverted and the flat end 70a thereof serves to maintain said pin below the level of the axis of the sector pinion 81.

As stated above, the quantity of fuel delivered to the engine by the fuel injection pump is regulated by the quantity of fuel that is diverted from the pump chamber to the pressure chamber 4a of the governor; and the quantity of such by-passed fuel is controlled by the sector pinion 81 and is equal to the difference between the total displacement of the injection pump and the amount of fuel delivered thereby to the engine. As the quantity of fuel delivered to the engine increases, the quantity of fuel by-passed to the governor decreases. The amount of fuel by-passed to the governor will also vary in all positions of manual adjustment of the by-pass control sector pinion 81.

The fuel pressure on the piston varies according to the square of the speed of the pump cam shaft; and when there is no hydraulic pressure on the governor piston 5, the spring 59 holds the piston against the adjustable stop pin 55 and the oscillatory sector pinion 81 is in maximum fuel feed position, in which position the quantity of by-pass fuel is reduced to a minimum. The pressure of the by-pass fuel is utilized by the governor for actuating the fuel quantity control sec-

tor pinion 81 of the pump through the piston 5 and connecting link 70 in accordance with the speed of the engine. The engine is set for the desired speed by manually adjusting the fuel feed control sector pinion 81 of the pump; and in each speed setting which corresponds to a particular orifice opening 1a, the sector pinion is automatically adjusted according to the speed and load conditions of the engine by the varying by-pass pressure transmitted to the sector gear operating piston 5 of the governor. A predetermined pressure in the by-pass system forces the piston 5 away from the stop 55 and against the pressure of the spring 59 and rotates the fuel feed control sector pinion 81 in the direction of decreased fuel supply. When the pressure in the by-pass system falls below such predetermined pressure, the piston 5 is forced by the spring 59 in the opposite direction and thus rotates said sector pinion in the direction of increased fuel feed.

By manipulating the throttle valve 12, the size of the orifice 1a may be varied to control the pressure in the chamber 4a and such pressure used to control the fuel feed control sector pinion 81 of the pump, thereby providing a pressure curve in the by-pass system which varies according to the square of the speed for each size of throttle orifice. Each size of throttle orifice 1a produces a different by-pass pressure curve which starts from zero but takes a different path as the speed rises. If the orifice 1a is large and allows the by-pass fuel to leak out without much pressure rise, a higher speed will be required to obtain a certain pressure than if the size of the orifice is smaller. Thus, as shown in the diagram of Fig. 15, for each position of the throttle or orifice control valve 12 there is a different curve of piston hydraulic pressure plotted against the speed. In this diagram, the number of revolutions per minute of the engine are shown as abscissa and the hydraulic pressure working on the governor piston is shown as ordinate. As shown in said diagram, the first constant pressure line above the zero line indicates the pressure produced by the governor spring 59 in its extended position; and the second constant pressure line indicates the pressure when said spring is compressed. If the throttle valve 12 is in nearly closed position, a curve B would result. The pressure curve B might indicate the idling position of the throttle, and the full load throttle position with the spring 59 extended would be reached at about 400 revolutions per minute. Any further increase in speed with the throttle orifice nearly closed would tend to increase the amount of fuel bypassed from the injection pump, since less fuel would be supplied to the engine. In such case, the curve B would take a more steep curve B' above the extended spring position and would reach no pumping or spring compressed position at about 450 revolutions per minute. When the throttle valve 12 is rotated to increase the size of the by-pass orifice 1a, the pressure curve C is obtained; and full throttle or spring extended position is reached at an engine speed of about 2,000 revolutions per minute. When this pressure is reached, the spring 59 starts to compress and reduce the quantity of fuel supplied to the engine, thus permitting more by-pass fuel to enter the governor. This action, of course, again increases the pressure more rapidly with speed during a fixed nozzle discharge condition. Accordingly, the hydraulic pressure plotted against the revolutions per minute follows a steep line C'

from the spring extended or full throttle position to the spring compressed or no throttle position, which is reached at about 2,100 revolutions per minute. It will be seen, therefore, that in the area below the spring extended position, the pump is always in full throttle adjustment, while in the area above the spring compressed position the pump is always pumping a minimum quantity of fuel. The area between these two lines represents the operating range of the fuel injection pump. For example, the dotted line D just below the spring compressed position on the diagram indicates a throttle position where just enough fuel is being pumped to the engine to overcome the friction thereof; and this throttle position would be the idling position of the engine regardless at what speed it occurred. In the normal operation of the engine, this idling position would occur somewhere between 400 and 450 revolutions per minute.

When the orifice 1a is entirely closed, while the engine is operating at extremely high speed, a pressure builds up in the by-pass system in excess of that required to operate the governor. In such event, the throttle valve 12 acts as a pressure relief valve; that is, said valve is forced upwardly off its seat by the excess pressure, thereby permitting the pressure to be dissipated through said valve and the passageway 10 leading therefrom to the supply tank. The oil-seals 25 and 27 associated with the throttle valve 12 prevent loss of pressure due to leakage around said valve and also prevent the entry of dust into the governor. Leakage is also prevented around the adjustable piston stop pin 55 and the adjustable anchor pin 65 for the extension spring 63 by means of the compressible sealing washers 58 and 69, respectively. The spring supporting bushing 64 slides free on the spring adjusting screw 65 throughout the greater portion stroke of the piston 5; and the idle spring 63 comes into play when the main governor spring 59 is almost fully compressed. The screw 65 may be adjusted axially so that the portion of the stroke on which the idle spring 63 acts can be adjusted to suit the particular pump controlled by the governor.

As stated above, the fuel pressure on the governor piston 5 varies in accordance with the square of the speed of rotation of the pump cam shaft. Accordingly, in order to obtain close governor regulation without the use of a piston operating spring having a variable rate of deflection, the variable motion link connection 18 between the piston 5 and the sector pinion 81 is provided, which connection forms a crank arm that is long enough to transmit ample turning movement to the sector pinion and, at the same time, provides a curve of piston travel compared to the sector pinion movement that is very close to a second power curve.

The split clamping ring 29 serves to retain the throttle valve and its mechanism in its supporting bore 8 and to take up any looseness of the bushing 22 in said bore. The clamping ring 29 also carries the stops for the throttle lever 32 and may be angularly adjusted relative thereto; said throttle lever is mounted on splines 33 on the throttle shaft 15, thus permitting said lever to be angularly adjusted relative to said shaft for operation by a pedal or hand operated mechanism regardless of the direction of movement of said mechanism.

Obviously, the hereinbefore described governor admits of considerable modification without departing from the invention. Therefore, I do

not wish to be limited to the precise details of construction shown and described, except as required by the scope of the appended claims.

What I claim is:

1. A speed governor for an internal combustion engine having a fuel feed control member and a source of fluid pressure varying with the engine speed, said governor comprising a housing, a cylinder in said housing, a piston positioned within said cylinder for reciprocal movement, a conduit connecting the source and said cylinder, resilient means tending to move said piston in one direction, the pressure in said cylinder tending to move said piston in opposition to said resilient means, an outlet orifice in said housing having communication with said cylinder for relieving the pressure therefrom, a manually adjustable throttle valve cooperating with said orifice for changing the size thereof to thereby change the rate of pressure variation in said cylinder, mechanical means for adjusting said resilient means, said throttle valve being arranged and constructed as a spring pressed check valve so that said valve will open when pressure within said cylinder exceeds a predetermined pressure.

2. A speed governor for an internal combustion engine having a fuel feed control member and a source of fluid pressure varying with the engine speed, said governor comprising a housing, a cylinder in said housing, a piston positioned within said cylinder for reciprocal movement, a conduit connecting the source and said cylinder, resilient means tending to move said piston in one direction, the pressure in said cylinder tending to move said piston in opposition to said resilient means, an outlet orifice in said housing having communication with said cylinder for relieving the pressure therefrom, a bore in said housing communicating with said orifice and a discharge passageway leading from said bore, a manually adjustable rotary disk valve mounted in said bore for throttling said orifice to thereby change the rate of pressure variation in said cylinder, mechanical means for adjusting said resilient means, said rotary disk valve being arranged and constructed as a spring pressed check valve so that said valve will open when pressure within said cylinder exceeds a predetermined pressure.

3. A speed governor for an internal combustion engine having a fuel feed control member

and a source of fluid pressure varying with the engine speed, said governor comprising a housing, a cylinder in said housing, a piston positioned within said cylinder for reciprocal movement, a conduit connecting the source and said cylinder, resilient means tending to move said piston in one direction, the pressure in said cylinder tending to move said piston in opposition to said resilient means, an outlet orifice in said housing having communication with said cylinder for relieving the pressure therefrom, a bore in said housing communicating with said orifice and a discharge passageway leading from said bore, a manually adjustable rotary disk valve mounted in said bore for throttling said orifice to thereby change the rate of pressure variation in said cylinder, said disk valve having an annular peripheral groove communicating with said discharge passageway for constantly relieving pressure within said cylinder in accordance with manual adjustment of said valve, and mechanical means for adjusting said resilient means, said rotary disk valve being arranged and constructed as a spring pressed check valve so that said valve will open when pressure within said cylinder exceeds a predetermined pressure.

4. A speed governor for an internal combustion engine having a fuel feed control member and a source of fluid pressure varying with the engine speed, said governor comprising a housing, a cylinder in said housing, a piston positioned within said cylinder for reciprocal movement, a conduit connecting the source and said cylinder, resilient means tending to move said piston in one direction, the pressure in said cylinder tending to move said piston in opposition to said resilient means, means on said housing and extending within said cylinder for limiting the extent of movement of said piston in said cylinder, an outlet orifice in said housing having communication with said cylinder for relieving the pressure therefrom, a manually adjustable throttle valve having a seat therefor cooperating with said orifice for throttling the same to thereby change the rate of pressure variation in said cylinder, mechanical means for adjusting said resilient means, said throttle valve being arranged and constructed as a spring pressed check valve so that said valve will open when pressure within said cylinder exceeds a predetermined pressure.

HERBERT C. EDWARDS.
